BALE TIE MAKING MACHINE

George K. Gaumer, Sterling, Ill., assignor to
Northwestern Steel and Wire Company, Ster-
ling, Ill., a corporation of Illinois

Application September 25, 1940, Serial No. 358,227

20 Claims. (Cl. 140—73)

This invention relates to high speed wire fabricating machinery and more particularly relates to machines for making bale ties at the rate of 90 to 100 per minute.

The invention will hereinafter be described as embodied in a high speed bale tie making machine, but it should be understood that machines of this invention are adapted for the fabrication of wire, rod, or strip articles in general.

According to this invention a plurality of wires are continually fed in spaced relation directly from an annealing furnace, drawing dies, or reels, through a cut-off mechanism into elongated wire guides. The feed mechanism is constantly driven and grips opposite sides of each wire. The cutter mechanism is intermittently operated to sever the wires received in the guides into desired lengths. Slack take-up springs are provided between the constantly driven feed mechanism and the intermittently operated cut-off mechanism to compensate for the momentary cessation of forward movement of the wires when the same are severed.

The severed wire lengths in the guides are then dumped from the guides into conveyors which laterally move the wire lengths in spaced parallel relation into work supports. These work supports may conveniently take the form of peripherally notched disks.

Each wire length deposited in the work support is longitudinally shifted to align an end thereof for a looping operation. A feature of this invention includes the provision of magnetic means for resisting the longitudinal shifting of the wire lengths in order that the same will only be moved the exact distance controlled by the aligner. The magnetic device imparts frictional resistance to the longitudinal shifting and prevents coasting of the wires beyond the desired position. In the high speed machines of this invention the aligner must operate with great rapidity and the magnetic device readily accommodates such rapid action.

The properly aligned wire length is then moved by the work supports into the loop-forming mechanism wherein the aligned end of the wire is bent around a twister head, the free end of the bent portion and the adjacent wire portion clamped by a vise and the twister head rotated to braid the wires together for forming a permanent open loop on the end of each wire length.

Another important feature of this invention includes the provision of a tie straightener which prevents bowing of the wire during the bending operation and aligns the portion of the wire ad-

jacent the bent free end portion in parallel relation with the bent free end portion for insuring a uniform braiding together of the contacting wire portions.

5 The work supports are next moved to discharge the finished bale ties and at the same time to receive a new wire length from the conveyor.

It is, then, an object of this invention to provide high speed wire, rod or strip fabricating machines capable of rapidly forming finished articles in uniform condition.

A specific object of this invention is to provide an improved bale tie making machine capable of automatically producing over 90 finished bale ties per minute.

10 Another object of this invention is to provide a feed mechanism for wire fabricating machinery which positively grips opposite side surfaces of each wire to impart positive movement thereto without damaging the gripped surfaces.

Another object of the invention is to provide improved wire severing apparatus having replaceable severing knives that can be readily adjusted to compensate for wear.

15 Another object of the invention is to provide knife holders in a wire severing mechanism which removably secure knives of inexpensive shape and which afford rapid adjustment and replacement of the knives.

Another object of the invention is to provide a rapidly operating wire length aligner.

20 Another specific object of the invention is to provide a magnetic device in a bale tie machine which imparts resistance to longitudinal shifting of wire lengths in the machine.

Another object of the invention is to provide a tie straightener mechanism in a bale tie machine which insures uniform looping of the wire end.

25 Other and further objects of the invention will be apparent to those skilled in the art from the following detailed description of the annexed sheets of drawings which, by way of example, illustrate a preferred embodiment of the invention.

On the drawings:

Fig. 27 is a broken side elevational view of a bale tie.

As shown on the drawings:

In general, the machine may be considered to consist of a wire feed mechanism which continually supplies a plurality of wires, a cutter mechanism which receives the wires from the feed mechanism and severs the same into wire lengths, a wire guide and release mechanism which holds the wire lengths and discharges the same into the machine when needed, a conveyor mechanism which receives the discharged wires from the guide mechanism, an aligner mechanism which evens up the ends of the wire lengths, a loop former mechanism which forms a looped end on the wire lengths, and a tie straightener mechanism which holds the wires so as to insure uniform formation of the loops.

For convenience each of the above mentioned

mechanisms will be described under a separate heading.

The wire feeder

5 The wire feed mechanism is best shown at 10 in Figures 1, 2 and 3. The mechanism 10 is illustrated as mounted on a frame 11 independent from the main frame of the bale tie machine.

A driven belt 12 drives a pulley 13 which pulley in turn drives the shaft 14 to rotate a jaw clutch 15 for driving a shaft 16. The jaw clutch 15 is controlled by a link 17 on a lever 18 pivotally supported on the shaft 14.

The shaft 16 is connected through pinions 19 to a large bevel gear 20. The bevel gear 20 drives a train of gears 21 which rotate the main drive shaft 22. Six feed rolls 23 are secured on the shaft 22 in spaced relation. Each feed roll 23 has a gear 24 bolted or otherwise secured thereto.

20 The feed roll mechanism 10 is provided with spaced guides 25 on each side of the feed rolls 23 and these guides extend above the rolls as shown. Bearing blocks 26 are slidably mounted in the guides and rotatably support top feed rolls 27 having gears 28 adapted to mesh with gears 24 on the feed rolls 23.

The bearing blocks 26 are vertically movable in the guides 25 and are spring pressed toward the bottom feed rolls 23 by means of coil springs 29 encased in housings 30 at the top of each bearing block. Adjusting bolts 31 are threaded through the tops of the housings 30 and act against the coil springs 29.

30 The teeth of the toothed portions 24 and 28 of the feed rolls are rather long so that they can engage even when the peripheries of the feed rolls are spaced apart for a considerable distance to accommodate wires W therebetween having large diameters. The top and bottom feed rolls are thus positively driven and no slippage can occur therebetween.

35 Each top feed roll is separately adjusted relative to its cooperating lower feed roll by means of an adjusting bolt 31.

The feed rolls grip the opposite sides of the wires W as best shown in Figure 3 and positively move each wire through a coil spring tube 32 (Figure 1) which serves as a guide into the cut off mechanism. The coil spring guides are adapted to be bowed against spring tension when the cut off mechanism momentarily stops the forward passage of the wires to accommodate an added length of wire since the feed mechanism continually feeds the wires into the tubes. The coil spring tubes therefore act as automatic slack take up mechanisms. When bowed by the increased lengths of wires therein the springs are stressed and tend to reassume an unstressed straight position thereby moving the wires through the cutter as soon as the cutter permits such movement.

The cutter

65 As shown in Figures 1, 4, 6, 8, 9 and 10, the wires W are pushed by the feed mechanism from the coil spring tubes 32 through an apertured die block 35 carried on standards 36 from the main frame F of the bale tie machine. The block 35 has six spaced apertures 37 therethrough each receiving a wire W directly from a tube 32. Each aperture preferably has a beveled mouth 37a (Fig. 9) for ready insertion of the leading ends of the wires into the die block.

70 As best shown in Figures 8 and 9 the face of the block 35 facing the cutter 10 is recessed in

the top portion thereof as at 35a. Six spaced semi-cylindrical recesses 35b depend from the recess 35a between the apertures 37. Six shafts 38 extend through the block 35 and project into the segmental cylindrical recesses 35b as shown. Arms 39 are secured on each shaft 38 and have rounded lower ends in spaced relation from the cylindrical walls of the recesses 35b. The arms 39 are adapted to swing in the recesses 35a and 35b.

The other ends of the shafts 38 have knife carrier blocks 40 secured thereon. One edge of each block 40 is grooved as at 40a to provide a guide for a knife 41. A second block 42 has a similar groove 42a for receiving the other edge of the knife. A block 42 is secured to each block 40 by means of bolts 43. The knives 41 operate close to the face of the die block 35 as best shown in Figure 9 and are forced through the wires W projecting through the apertures 37 to cut off the leading ends of the wires.

Each knife is removably held by the blocks 40 and 42 and can be readily adjusted in the blocks. The knives can thus assume a simple square rod shape with one end sharpened to provide a sharp cutting edge. As the knives need regrinding they can be removed from the blocks, sharpened, and readily replaced in the blocks. They are adapted to project from the blocks for any desired distance and thus can be used after repeated grinding operations which materially shorten their length.

The arms 39 are all pivoted to a single bar 44 which is loosely linked to an operating arm 45 which is keyed on a shaft 46. When the shaft 46 is rotated to turn the arm 45 the bar 44 is rocked to move all of the arms 39 for driving the cutter knives 41 past the apertures 37 and thus sever any wires projecting from the apertures. It will be noted that the sharpened end of each knife 41 is beveled in a direction away from the block 35 so that, during the severing operation, the leading ends of the wires are moved by the cutters into spaced relation from the block.

The operating arm 45 has a tail portion 45a (Fig. 8) pressed by a spring 47 to return the cutters to their initial position after each cutting operation.

As shown in Figures 4 and 6, the end of the shaft 46 has a yoke 48 therearound anchored in the end of an arm 49. The arm 49 is thus suspended from the shaft and can swing longitudinally of the shaft.

A pin 50 is threaded through the end of the arm 49 and seated into a recess in the shaft 46 so that the shaft will be rotated when the arm is raised. However, the pin does not interfere with swinging movement of the arm.

The free end of the arm 49 has a shoe 49a thereon adapted to be projected into the path of a roller 51 on a large constantly driven gear 52. The gear 52 meshes with a pinion 53 on a shaft 54 extending to the feed mechanism as shown in Figure 1 and driven by the shaft 16 of the feed mechanism through the bevel gears 19 as shown in Figure 2.

An intermediate portion of the arm 49 has a strap 49b thereon receiving a rod 55. The rod 55 extends into the groove 56a of a cam 56 as best shown in Figure 6. The cam 56 has a gear 57 thereon meshing with a gear 58 on a shaft 59. The shaft 59 has a ratchet 60 (best shown in Figure 7) thereon driven by a pawl 61 on the end of a lever 62. The lever 62 carries a roller 63

actuated by means of a cam 64 on a main drive shaft 65. The gear 52 is secured to the main drive shaft 65 and constantly rotates this shaft.

It will be noted that the ratchet 60 has eight teeth thereon. The cam 64 on the main shaft 65 actuates the pawl 61 once for each revolution of the shaft 65. The pawl, in turn, advances the ratchet 60 a distance of one tooth for each revolution of the shaft 65. Therefore the shaft 59 is rotated only once for every eight rotations of the shaft 65. The rotation of the shaft 59 moves the cam 56 to longitudinally shift the rod 55 for moving the shoe 49a of the arm 49 into the path of the roller 51 on the large gear 52. As the shoe 49a rides over the roller 51 the arm 49 is tripped to rock the shaft 46 and effect the rocking of the bar 44 to move the cutters. As soon as the roller 51 has cleared the shoe 49a the spring 47 returns the shaft 46 and moves the cutters to neutral position.

The wire guides and release mechanism

As shown in Figures 1, 6 and 11 the wires are pushed through the cutter apertures 37 directly into elongated open bottom guides 70 suspended from arms 71 of brackets 72 secured at spaced intervals to the rear portion of the main frame F. The guides 70 extend along the full length of the machine as shown in Figure 1 from the cutter and are aligned with the apertures 37 in the cutter.

Closure bars 73 (Figure 11) close the open bottoms of the guides 70 and are supported on fingers 74 carried by a bar 75 which is slidably mounted in tracks 76 on each arm 71.

The rear ends of the bars 75 are pivoted to arms 77 which are keyed on the shaft 46 described above. Every time the shaft 46 is rocked by tripping of the arm 49 as the shoe 49a rides over the roller 51, the arms 77 are rocked to move the fingers 74 for carrying the bars 73 past the over the roller 51, the arms 77 are rocked to move the guides 70 simultaneously with the actuation of the cutters so that the wire lengths in the guides can drop by gravity out of the open bottoms of the guides.

The conveyors

As best shown in Figure 11 the wires W, upon being released from the guides 70, fall by gravity into the pockets P of endless conveyors 80 which extend under the guides. These conveyors 80 move laterally in the machine and are trained around rear sprockets 81 which are keyed on the shaft 59 as shown in Figure 7. Idler sprockets 82 (Figure 11) are loosely mounted on a shaft 83 extending longitudinally in the machine in spaced parallel relation in front of the shaft 59.

Each conveyor 80 is built up of a plurality of chain links carrying triangular support members 84 having their apexes in spaced relation and having sloping sides defining the pockets P for receiving the wires.

Since the rear sprockets 81 are secured on the shaft 59, they are driven by the ratchet 60 and each time the pawl 61 actuates the ratchet the conveyors 80 are moved forwardly one step. Thus six wires are simultaneously deposited in the conveyors and the conveyors are then moved a step at a time so that the sixth wire is moved out from under the guides before the shaft 46 is again tripped to release a batch of six new wires.

As shown in Figure 6, the conveyors 80 are spaced at intervals along the length of the machine under the guides 70.

The conveyors 80 dump the wires, one at a time, onto inclined ways 85. The wires fall by gravity along the ways 85 into the notches 86 of peripherally notched disks or work supports 87 mounted at spaced intervals along the length of the machine on a shaft 88.

The shaft 88 is driven through a ratchet 89 secured thereon, by a pawl 90. The pawl 90 is pivotally mounted on a bell crank 91 which is oscillated by a cam 92 on the main cam shaft 93 of the machine. This main cam shaft 93 is driven from the shaft 65 through a gear train 94 as shown in Figure 6. The middle gear of the train of gears 94 is mounted on an idler shaft 95.

A large diameter gear 96 is loosely mounted on the end of the shaft 93 and carries a pawl and ratchet device as best shown in Figure 5. As therein indicated, a ratchet 97 is secured to the gear 96 and is driven by a pawl 98 pivotally mounted in a housing 99. The housing 99 is oscillated by means of a crank 100 having a driving arm 101 pivoted to the large gear 52 in spaced relation from the axis of the gear. It will be noted that the ratchet 97 only has three teeth so that the large gear 96 is only moved through one revolution for each three revolutions of the gear 52, for a purpose to be hereinafter described.

The aligner mechanism

In order that the cut ends of the wires deposited into the work support disks 87 be aligned uniformly, it is necessary to longitudinally shift each cut wire length as soon as it is deposited into the notches 86 of the disks. The wires are purposely initially deposited in the disks so that the ends thereof to be looped are spaced too close to the inlet end of the machine for proper action by the looping device. In accordance with this invention, therefore, as shown in Figure 18, a pusher 105 is mounted in the path of the cut ends of the wire adjacent the first disk 87. This pusher 105 is carried on an arm 106 having a pin 107 riding in a cam groove 108 of a cam 109 secured on the main cam shaft 93.

The pusher 105 is actuated by the cam 109 to longitudinally shift each wire length W in the supporting disk 87 for properly aligning the ends of the wires. Since the machine is operating at high speed, the pusher 105 must travel at a high rate. The impulse of each wire caused by the pusher may be sufficient to cause a longitudinal coasting of the wire beyond the desired position.

According to this invention, therefore, as best shown in Figures 12 and 13, a permanent magnet 110 in the form of a segmental circular shoe is stationarily mounted adjacent the first disk 87 in the path of the wires carried by the disk. This magnet creates a magnetic field around the wires which arrests any objectionable coasting of the wire beyond the position created by the pusher. The permanent magnet also serves to securely hold the wires in the notches of the disk 87.

As shown in Figure 13 the magnet only extends around the top portion of the disk so that the wires can be dumped out of the disk after the looping operation hereinafter described.

While a permanent magnet shoe 110 is preferred it is obvious that an electromagnet can be used. The periphery of the magnet is circular to follow the contour of the wires when fully seated in the notches of the disk.

The loop former

As best shown in Figures 12 and 19, the disks 75

87 move the wires over a stationary anvil 111. The disks feed one wire at a time to the anvil 111. A vise 112 carries a gripper block or hammer 113 above the anvil 111. The vise 112 is pivoted as at 114 and has a dependent cam actuated lever 114a to open and close the vise so that the gripper will clamp the wire on the anvil 111 by mechanism hereinafter described.

A twister member 115 carries a dependent loop shaping pin 116 at its forward edge and is supported on a rotatable shaft or head 117. The shaft 117 is driven by a gear 118 meshing with the large gear 96 described above.

The member 115 is pivotally supported on the end of the shaft 117 and has a spring urged tail portion 115a (Fig. 20B) adapted to be engaged by a slidably collar 120 slidably mounted on the shaft 117 and actuated by a yoked arm 121. The arm 121 is controlled by a cam 122 on the main cam shaft 93 as best shown in Figure 23. When the cam 122 trips the arm 121 to slide the collar 120 over the tail 115a of the tripper member 115 the pin 116 will be moved out of the loop of the finished bale tie as hereinafter described.

The arm 121 carries a roller 123 held on the operating face of the cam 122 by means of a spring 124 as shown in Figure 23.

A looping pin 125 is carried on the end of an arm 126a of a forming post 126 as best shown in Figure 16. The forming post 126 is mounted in an upstanding cylindrical bushing 127 pressed into a housing 128. The arm 126a provides a shoulder 126b riding on the enlarged end 127a of the bushing 127 so as to have a substantial contact therewith.

As shown in Figure 15 a V-notch 126c is cut in the arm 126 to communicate with a vertical groove 129 along the post 126 for providing an oil groove throughout the entire length of the cylinder 127.

The lower end of the post 126 has a beveled pinion 130 keyed thereon by means of a key 131. The pinion is held on the post by means of a nut 132.

As best shown in Figure 14, the pinion 130 meshes with gear teeth 133 on an arm 134 carried by a short stub shaft 135 from the bracket 128. The other end of the arm 134 carries a pin 136 riding in a groove 137 of a cam 138. As shown in Figure 23, the cam 138 is secured on the main cam shaft 93.

As illustrated in Figure 21 the looping pin 125 abuts one side of the wire W while the twister pin 116 abuts the other side of the wire W. The post 126 is then rotated to move the pin 125 for bending the wire around the twister pin 116 as shown in Figure 22.

The end of the wire is thus looped.

The vise 112 is next actuated by a cam surface 137a on the cam 138 acting against a roller 114b on the lever 114a (Fig. 23) to move the gripper 113 on top of both portions of the wire as shown in Figure 22 for clamping the wire portions against movement. A spring S holds the roller 114b on the cam surface 137a as shown in Figure 23 and opens the vise when the roller rides on the low spots of the cam.

The twister pin 116 is next rotated by rotation of the shaft 117 to twist the looped end and form a braid twist T to produce the finished bale tie B. T. as shown in Figure 27.

After the twisting operation the vise 112 is opened, the collar 120 moved on the shaft 117 against the tail portion of the twister 115 to move the pin 116 out of the loop and the disks 75

are rotated to discharge a finished bale tie out of the machine and to bring a new wire length over the anvil 111.

The tie straightener

Since the wrapping of the wire around the twister pin 116 as illustrated in Figures 21 and 22 is apt to cause a bowing of the wire between the anvil and the pin 116, which would interfere with a twisting together of the free end of the wire and the adjacent intermediate portion of the wire, the present invention now provides a straightener member 140 slidably carried by the vise 112 on a pin 140a (Fig. 20A) and adapted to thrust against the wire to prevent a bowing 15 of the same during the looping operation and to cooperate with the looping pin 125 for laying the free end of the wire tightly against the intermediate portion of the wire around which it is to be twisted.

As shown in Figures 19, 20 and 20A, the vise 112 has ears 141 on one side thereof pivotally supporting a lever 142 which is pivoted at its lower end to the member 140. The upper end of the lever 142 lies in the path of a block 143 slidably mounted on the vise 112 and having an inclined surface 143a adapted to act on the lever 142. The block 143 has a boss 143b through which extends a rod 144. A coil spring 145 is disposed around the rod 144 on the other side of the boss 143b and the rod has an enlarged head 144a for retaining the spring between the head and the boss.

The rod 144 is connected through a flexible coupling 146 with a second rod 147 carried in the end of a lever 148. The lever 148 is pivoted at 149 to the frame F of the machine as shown in Figure 19 and extends below the frame as shown. The lower end of the lever carries a roller 150 actuated by a cam 151 carried on the main cam shaft 93. The cam is adapted to throw the lever for sliding the block 143 relative to the vise 112 thereby causing the beveled portion 143a of the block to tilt the lever 142. This causes the tie straightener member 140 to move from the position shown in Figure 21 to the position shown in Figure 22 against the wire W. This action occurs simultaneously with the movement of the looping finger 125 from the position shown in Figure 2 to the position shown in Figure 22. As a result, the free end portion of the looped wire is held tightly against an intermediate portion of the wire for an appreciable distance as shown in Figure 22. The vise then closes on the two adjacent portions of the wire and the looping finger 125 as well as the straightener member 140 are moved back to the position shown in dotted lines in Figure 22. The twisting pin 116 is then rotated to braid the looped end of the wire. The tie straightener is thus positively controlled by cam action to squeeze the wire and to back off from the wire during the twisting operation. The vise 112, when opened, moves the straightener therewith out of the path of the finished bale tie B. T.

The straightener member 140 insures the contacting relation between the free end portion of the looped wire and an intermediate portion of the wire as shown in Figure 22 so that the anvil and vise will tightly grip both portions of the wire while the twisting operation produces a uniform tight braided twist on each wire.

The tie straightener thus cooperates with the looping pin to squeeze the wire portions laterally into contacting relation. The anvil and vise 75

squeezes the wire portions in a single horizontal plane.

Summary

From the above descriptions, it should be understood that the present invention now provides a high speed bale tie machine which uniformly produces bale ties having twisted looped ends. The various parts of the machine are controlled through positively driven members including cams.

A feature of the invention includes the provision of a main cam shaft which positively controls movement of the work supports, the wire aligner, the looper, tie straightener, the stripping of the twister from the loop, and the vise. Positive control of these elements from a single shaft makes possible an exact timing of the machine mechanisms so that the machine can be run at very high speeds.

Machines of the present invention can produce from three to four times the number of bale ties heretofore produced by any prior known machine in the same length of time.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A bale tie machine comprising positively driven pairs of feed rollers gripping a plurality of wires therebetween, a plurality of open bottomed elongated guides receiving the wires from the feed rolls, shiftable closures for said guide bottoms to retain the wires therein, an apertured block between the feed rolls and guides receiving the wires through the apertures thereof, knife carriages rockable over the face of the block where the wires emerge, knives detachably secured in said carriages, a rock shaft for moving the knives past the apertures to sever the wires and for shifting said guide closures to discharge the severed wires out of the guides, conveyors beneath the guides receiving said wires, a main drive shaft, a pawl and ratchet connection between said main drive shaft and said 40 conveyors for moving the conveyors to advance the wires step by step, peripherally notched work supports receiving the wires from the conveyors, a main cam shaft driven from said main drive shaft, a cam and ratchet connection between said cam shaft and said work supports to rotate the supports for advancing the wires around the top portions thereof, a pusher successively engaging the end of each wire in the work supports to longitudinally shift said wires, a magnet acting 50 on the shifting wires to arrest movement of the wires beyond the stroke of the pusher, a gripper receiving each shifted wire therebetween, a looper for looping the end of the wire, a wire straightener movable against the wire to cooperate with the looper for eliminating bowing of the wire, and cams on said main cam shaft actuating said pusher, gripper, looper and straightener.

2. A bale tie machine comprising a plurality of feed rolls secured on a single shaft, a cooperating vertically shiftable feed roll for each roll on the shaft, gear teeth connecting the feed rolls into positively driven pairs each receiving a wire therebetween, spring means urging the vertically shiftable feed rolls toward their cooperating rolls

to grip the wires therebetween, elongated open bottomed guides receiving the wires from the feed rolls, shiftable closures for the guide bottoms to retain the wires therein, an apertured block between the feed rolls and the guides receiving the wires through the apertures thereof, rockably mounted knife grippers on the apertured block, knives clamped in each gripper, means for rocking said grippers to move the knives past the apertures in the block for severing the wires, means for shifting said closures to discharge the severed wires out of the guides, peripherally notched rotatable work supports, conveyors receiving the wires from said guides to successively feed the same into the work supports, a pusher 10 successively engaging the end of each wire to longitudinally shift the wire in the work supports, a magnet cooperating with the shifting wire to arrest movement thereof beyond the stroke of the pusher, a looper for looping the end of each wire, a wire straightener cooperating with said looper to clamp the looped end of the wire against an intermediate portion of the wire, and a positively driven cam shaft actuating said looper and said straightener.

3. A bale tie machine comprising a plurality of pairs of positively driven feed rolls receiving wires therebetween, gears connecting the feed rolls of each pair, a resilient shiftable mounting for one feed of each pair, elongated supports receiving the wires from the feed rolls, cutters for severing the wires seated in said supports, conveyors receiving the severed wires from the supports, peripherally notched work supports receiving the wires from the conveyors, a pusher for longitudinally shifting the wires in the work supports, means for arresting the shifting of each wire beyond the stroke of the pusher, a looper for looping the end of each wire, a wire straightener cooperating with said looper, and a cam shaft positively actuating said looper and said wire straightener.

4. In a bale tie machine a feed mechanism comprising a driven shaft, a plurality of feed rolls keyed on said shaft, peripheral teeth on each of said feed rolls, a plurality of vertically shiftable bearings above said feed rolls, a top feed roll in each of said bearings having teeth adapted to match with said first mentioned teeth, and adjustable means for urging the top feed rolls toward the first mentioned feed rolls to provide a plurality of pairs of positively driven rolls each adapted to grip opposite surfaces of a wire passed therebetween.

5. In a bale tie machine a plurality of pairs of positively driven feed rolls for gripping opposite surfaces of a plurality of wires, an apertured block receiving said wires through the apertures thereof, rock shafts extending through said blocks, knife carriages secured on said rock shafts, knives detachably clamped in said carriages and projecting therefrom at selected distances toward the apertures in the block, and arms for oscillating said rock shafts to move the knives past the apertures for severing the wires emerging therefrom.

6. In a bale tie machine including rotatable wire supports, the improvement which comprises a stationary magnet acting on wires in said supports to resist movement of the wires for holding the wires in the supports.

7. In a bale tie machine including rotatable work supports and a pusher for longitudinally shifting wires in said supports, the improvement which comprises a magnet acting on said wires

to resist said pusher for holding said wires from shifting beyond the stroke of said pusher.

5 8. In a bale tie machine including a peripherally notched rotatable work support receiving wires in the notches thereof, the improvement which comprises a stationary segmental cylindrical magnet shoe adjacent said work support for acting on wires in the support to resist movement thereof.

15 9. In a bale tie machine including a peripherally notched rotatable disk receiving wires in the notches thereof and a pusher for longitudinally shifting the wires, the improvement which comprises a stationary segmental cylindrical magnet shoe adjacent said disk for creating a magnetic field resisting movement of the wires in the notches of the disk.

20 10. In a bale tie machine including a peripherally notched rotatable disk receiving wires in the notches thereof, the improvement which comprises a segmental cylindrical magnet shoe stationarily mounted adjacent said disk and extending around the top portion only of the disk.

25 11. In a bale tie machine including rotatable work supports, a movable wire gripper, a looper, a wire straightener for backing up the wire during the looping operation, and a wire pusher, the improvement which comprises a single main cam shaft and cams on said shaft for driving said work supports, said gripper, said looper, said wire straightener and said wire pusher in timed sequential relation.

30 12. In a bale tie machine a looper comprising an elongated post having an annular shoulder near the top thereof, an arm projecting laterally from the top of said post, a pin extending upwardly from said arm, an elongated cylindrical boss receiving said post and having a wide rimmed portion supporting said shoulder, and 40 said post and said boss cooperating to provide an oil groove therebetween for lubrication of the post throughout the entire length of the boss.

35 13. In a bale tie machine including a device for looping an end of a wire, the improvement which comprises a wire straightener for abutting the wire, a lever sliding said member toward and away from the wire, and a positively driven cam for tilting said lever to effect abutment of the straightener against the wire during the looping operation and for thereafter spacing the straightener from the wire.

45 14. In a bale tie machine including an anvil for receiving a wire thereover, a rockably mounted gripper cooperating with the anvil to clamp the wire therebetween, a twister pin, and a looping arm for bending the wire around the pin to lay the end of the wire over the anvil, the improvement which comprises a slidably mounted wire straightener backing up the wire during the bending operation and cooperating with the looping arm to bring the bent end of the wire into full line contact with an appreciable length of the adjacent intermediate wire portion extending over the anvil, a lever tiltably mounted 50 on the gripper for actuating said straightener, a slidable block on said gripper having a surface for tilting said lever to move the straightener toward and away from the wire, a driven cam, a vertical lever tilted by said cam, and a flexible linkage between said vertical lever and said slideable block.

55 15. In a bale tie machine including a cam shaft and a wire looper driven thereby, the improvements which comprise a wire straightener for said machine adjacent said looper to abut

the loop forming portion of the wire immediately next to the portion directly acted on by the looper to prevent bowing of the wire and means connecting said straightener with said cam shaft to positively operate the straightener at properly timed intervals.

16. In a bale tie machine including a twister pin, a looping arm for bending a wire around said pin, and a pair of clamping jaws for holding the bent wire, the improvement which comprises a shiftable wire straightener cooperating with said looping arm to hold an intermediate portion of the wire against the bent free end of the wire, and a positively driven cam for shifting said straightener.

17. In a bale tie machine the improvement which comprises a vertical cylindrical boss fixedly mounted on said machine, a forming post extending through said boss and having an annular shoulder riding on top of the boss, a looping pin on said post in spaced relation from the axis of the boss, a pinion secured on the lower end of said post beneath said boss, and an arcuate gear segment engaging said pinion to rotate the post.

18. In a bale tie machine including means for feeding a plurality of wires and an apertured block receiving the wires through the apertures thereof, the improvements which comprise knife carriages rockably mounted on said block adjacent each aperture therein, elongated knives

5 detachably mounted in said carriages, and projecting therefrom at selected distances for movement past the apertures to sever wires emerging therefrom and means for rocking said carriages to move said knives toward and away from said apertures whereby the knives can be removed from the carriages for sharpening and replaced in the carriages to project the desired amounts therefrom.

10 19. In a bale tie machine including a twister pin, a looping arm for bending a wire around said pin, an anvil for receiving the wire thereover, and a movable clamping jaw cooperating with said anvil to hold the bent wire, the improvement which comprises a wire straightener 15 movably mounted on said clamping jaw and cooperating with said looping arm to hold an intermediate portion of the wire against the bent free end of the wire, and means for moving said wire straightener on said clamping jaw toward and away from said intermediate portion of the wire.

20 25 20. In a bale tie machine including a twister pin, a looping arm for bending a wire around said pin, and clamping jaws for holding the bent wire, the improvement which comprises a wire straightener intermediate the clamping jaws and twister pin to abut the loop forming portion of the wire immediately next to the portion directly acted on by the looping arm to prevent bowing 30 of the wire during the looping operation.

GEORGE K. GAUMER.
